CHARLES A. MECHLING, DAVID L. THOMAS, AND JAMES H. KUHNS, OF TULSA, OKLAHOMA; SAID KUHNS ASSIGNOR TO SAID MECHLING.

ROPE-CLAMP.

1,035,891.

Specification of Letters Patent. Patented Aug. 20, 1912.

Application filed October 17, 1911. Serial No. 655,243.

To all whom it may concern:

Be it known that we, CHARLES A. MECHLING, DAVID L. THOMAS, and JAMES H. KUHNS, citizens of the United States, residing at Tulsa, in the county of Tulsa and State of Oklahoma, have invented certain new and useful Improvements in Rope-Clamps, of which the following is a specification, reference being had therein to the accompanying drawing.

This invention relates to an improvement in rope clamps and more particularly to clamps of this character which are designed especially for use in connection with well drilling apparatus, although the invention is susceptible to other uses. It is well understood that clamps of this character when used in connection with the cables of well drilling apparatus are subjected to great strains, and the object of the present invention is the provision of a strong and durable clamp of this character which may be readily clamped to the cable tight enough to prevent any slipping when in use and thus spoiling the cable.

A further object of the present invention is the provision of a clamp of this character of such a construction that it may be readily and easily positioned onto the cable or rope.

A further object of the invention is the provision of a clamp of this character of such a construction that it may be readily adapted for use in connection with cables of various sizes.

Other objects of the invention will be apparent from a detailed description herein-after when read in connection with the accompanying drawings forming a part hereof, wherein a convenient embodiment of the invention is illustrated and wherein like characters of reference refer to similar parts in the several views.

In the drawings: Figure 1 is a front elevation of the improved clamp; Fig. 2 is a horizontal cross section through the central portion of the clamp, the clamping jaws thereof being shown in open position; Fig. 3 is a similar view showing the clamping jaws in their closed position; Fig. 4 is a side elevation; Fig. 5 is a top plan view of the clamp showing the same applied to a cable; Fig. 6 is a longitudinal section of the removable liners used in connection with the clamping jaws; Fig. 6a is a top plan

view thereof; Fig. 6b is a bottom plan view thereof, and Fig. 7 is a cross section through the clamping jaws showing the removable bearing faces employed in conjunction therewith.

Referring now more particularly to the drawings, A designates the body of the clamp which is provided with an opening B extending longitudinally therethrough and with a slot B' formed in the wall thereof and opening into the opening B in the body A. The body A is conveniently formed of cast metal and is substantially cylindrical in form. The body A is also conveniently provided at the upper and lower portions thereof with strengthening flanges a which are formed integral therewith and which extend around the body and terminate at the slot B' formed therein. Projecting laterally from the body A at one side of the slot B' formed therein, and between the upper and lower flanges a thereof, is an arm C which is preferably cast integral with the body A and the inner face of which is positioned in substantially the same plane as one of the walls of the slot B' in the body A.

The opening B which extends longitudinally through the body A of the clamp, is provided with a curved wall which in the present embodiment of the invention is shown as being formed on the arc of a circle; and rigid with the body member A of the clamp and projecting into the opening B extending longitudinally therethrough is a sector shaped jaw member D, the curved base of which constitutes a continuation of the curved wall of the opening B in the body A of the clamp. The sector shaped jaw member D is conveniently cast integral with the body A of the clamp although any other construction may be employed in which the jaw member is rigid with said body member. The sector shaped jaw member D projects for a substantial distance above and below the body member of the clamp and is so positioned relatively to the arm C, heretofore described, that one of the radial faces thereof extending inwardly at an angle from the inner end of the inner face of the arm C, and such radial face of the jaw member is provided with a curved seat extending for the full length thereof in which is removably secured a boxing D', the face of which is flush with the radial face of the jaw member D in

which it is secured and is provided with a cable receiving groove *d* extending the full length thereof.

Any suitable means may be provided for 5 removably securing the boxing *D'* in its seat in the jaw member *D* and in the form of the invention illustrated in the drawings we have shown screws *d'* which pass through the projecting ends of the jaw member *D* 10 and engage the end portions of the boxing *D'*. Fitting within the opening *B* which extends longitudinally through the body member *A* of the clamp, is a movable jaw member *E* which is co-extensive 15 in length with the fixed jaw member *D* heretofore described, and the ends of which project above and below the top and bottom of the jaw member *A*. The jaw member *E* is in the shape of a sector, the radius of 20 which is substantially the same as the radius of the sector shaped fixed jaw *D* and the outer curved wall of the jaw member *E* is formed on the same arc as the curved wall *b* of the opening *B* extending through the 25 body *A* of the clamp. The cross sectional area of the movable jaw member is considerably less than the cross sectional area of the opening *B* of the body member *A* so that said jaw is free to oscillate in such 30 opening with its curved wall in contact with the curved wall of the opening. The radial face of the sector shaped jaw member *E* adjacent the slot *B'* in the wall of the clamp *A* is provided with a curved seat therein in 35 which is removably secured a boxing having a cable receiving groove extending for the full length thereof, these parts being similar in construction to the boxing *D'* heretofore described in connection with the 40 fixed jaw *D*. The cable receiving groove of the boxing which is carried by the movable jaw is adapted to coöperate with the cable receiving groove of the boxing carried by the fixed jaw to form a socket in which the 45 cable of the well drilling apparatus is adapted to be clamped, and from the construction thus described it will be noted that the socket thus formed is positioned at one side of the center of the circle on which the 50 curved wall *b* of the opening *B* in the clamp is formed, so that as the movable jaw *E* is oscillated in said opening, the boxing carried thereby will be caused to approach the boxing on the fixed jaw *D* so that the cable 55 will be securely clamped in the grooves carried by said boxings. From the construction above described it will also be noted that when the rear faces of the jaw members *D* and *E* are in contact, as shown in Fig. 2, 60 the cable receiving socket formed by the grooves in the removable boxings carried by said jaw will be closed at its rear and open at its front so that the cable may be readily guided into said socket and the clamp properly positioned thereon by merely drawing 65

the clamp onto the cable with the inner face of the upwardly projecting arm *C* of the clamp in contact therewith.

Projecting outwardly from the movable jaw member *E* and positioned intermediate the ends thereof, is an arm *F*, which is positioned directly opposite the fixed arm *C* projecting outwardly from the body *A* of the clamp and is conveniently of substantially the same size as said fixed arm. The 7 wall of the body *A* of the clamp is provided with a recess *a'* opening into the slot *B'* formed therein and positioned between the reinforcing flanges *a* at the top and bottom thereof, which recess is of substantially the 8 same width as the arm *F* extending outwardly from the movable jaw and serves to receive the same when the movable jaw is oscillated. This construction also serves to prevent endwise movement of the movable 8 jaw in the opening *B* of the clamp.

Formed integral with the portions of the fixed and movable jaws *D* and *E* and projecting above the body *A* of the clamp are suitable eyes which are adapted to receive 9 the usual supporting chains. These devices are well known in this art, and we have therefore deemed it unnecessary to illustrate the same.

Any desired means may be employed for 9 adjusting the movable jaw *E* relative to the fixed jaw *D*, to effect the clamping or release of the cable therebetween. In the form of the invention illustrated in the drawings, we have shown means for this purpose which enables a rapid and efficient adjustment of the jaws. In the construction shown the outer end of the arm *C* which projects laterally from the body member *A* of the clamp is provided with a pair of outwardly extending pins *g* upon which is slidably mounted a block *G* from the ends of which project pintles *g'*.

H designates a bail, the arms of which are pivotally supported by their free ends 11 upon the pintles *g'* projecting from the ends of the block *G* and the end of which is adapted to embrace the free end of the arm *F* projecting from the movable jaw *E* and to engage a curved seat *h* positioned on the 11 outer face thereof.

I designates an operating screw which has a threaded engagement with the block *G* and the inner end of which is adapted to engage a suitable socket formed in the outer face of the arm *C* projecting from the body member *A* of the clamp. The outer end of the operating screw *I* is provided with an operating handle *I'* of any suitable construction.

In the use of the device the arm *F* projecting from the movable jaw member *E* is moved away from the arm *C* projecting from the body member *A* of the clamp as far as possible and the clamp is then placed 11

- upon the cable by drawing the same over the cable, causing it to pass between the arms F and C and into the cable receiving socket formed by the coöperating cable 5 grooves of the jaw members. The bail H is then swung over the outer end of the arm F projecting from the movable jaw member E and the handle I' of the operating screw II is actuated to shift the block 10 G away from the arm C projecting from the body member of the clamp, which will serve to draw the arm F toward the arm C and effectively clamp the cable in its socket. By reason of the eccentric positioning of the 15 cable socket heretofore described, a very slight movement of the operating screw I will serve to move the jaws to clamping position and it will also be seen that by this construction, the clamp may be effectively 20 secured to the cable by the application of a small amount of power to the operating handle I' and that when so secured there is practically no danger of any slipping of the clamp on the cable.
- 25 An important feature of the present invention is the removable boxings which are provided for the jaw members of the clamp, as not only may these boxings be removed and replaced when they become worn, thus 30 prolonging the life of the clamp indefinitely, but also by providing a number of sets of boxings having different size cable receiving grooves therein it is possible to use the same clamp with cables of different sizes, whereas 35 at the present time it is the custom to provide a separate clamp for each cable.
- While a convenient embodiment of the invention is illustrated in the accompanying drawings, it will be obvious that many 40 changes may be made to the form and construction therein shown without departing from the spirit and scope of the invention as defined in the appended claims.
- We claim:—
- 45 1. In a rope clamp, a body provided with a longitudinally disposed opening therein, a jaw member projecting within the opening in said body, a second jaw member positioned within the opening of the body member and free to oscillate therein, and means 50 for adjusting said jaw members relatively to each other the upper ends of said jaws being provided with means for suspending the clamp.
- 55 2. In a rope clamp, a body provided with an opening extending longitudinally thereof, said opening being provided with a wall curved on the arc of a circle, a jaw member projecting within the opening in the body 60 of the clamp, a second jaw member fitting within the opening in said body and provided with a curved wall conforming to the curvature of the curved wall of the opening, the adjacent faces of the jaw members being 65 provided with coöperating cable receiving
- portions therein, positioned eccentric to the center of and within a circle including the curved wall of the opening in the body, and means for adjusting said second jaw member relatively to said first mentioned jaw 70 member.
3. In a rope clamp, a body provided with an opening therein extending longitudinally thereof, said opening being provided with a wall curved on the arc of a circle, a sector shaped jaw member rigid with said body and projecting into the opening therein, a movable sector shaped jaw member mounted in the opening in said body and provided with a curved wall conforming to the curvature of the curved wall in the opening in the body, the adjacent faces of said jaw members being provided with coöperating cable receiving recesses eccentric to a circle including the curved wall of the longitudinal opening in the body, and means for adjusting said movable jaw member relative to said rigid jaw member. 75 80 85
4. In a rope clamp, a body provided with a longitudinally disposed opening therein, and with an opening in the wall thereof communicating with said longitudinal opening, a jaw member positioned within the longitudinally disposed opening in the body, a movable jaw member mounted in the longitudinally disposed opening in the body and free to oscillate about the longitudinal axis thereof, an arm projecting laterally from said movable jaw member through the opening in the wall of the body member, and means interposed between said arm and the body for oscillating said movable jaw member to move the same into and out of clamping relation to said first mentioned jaw. 90 95 100 105
5. In a rope clamp, a body provided with a longitudinally disposed opening extending therethrough and with a longitudinally disposed slot in the wall thereof communicating with said opening, said body being provided with a laterally extending recess intermediate the top and bottom thereof, opening into one edge of said longitudinal slot in the wall of the body, a jaw member positioned within the longitudinally disposed opening in the body, a movable jaw member mounted to oscillate in the longitudinally disposed opening in the body, an arm projecting laterally from said movable jaw member and movable in the laterally extending recess in the wall of the body of the clamp, and means interposed between said arm and the body of the clamp to shift said movable jaw. 110 115 120
6. In a rope clamp, a body provided with a longitudinally disposed opening extending therethrough, and with an opening in the wall thereof communicating with said longitudinally disposed opening, a jaw member projecting within the longitudinally dis- 125 130

- posed opening in the body, a movable jaw member mounted to oscillate in said opening and to coöperate with said first mentioned jaw member, an arm rigid with said body 5 and projecting laterally therefrom, an arm projecting laterally from the movable jaw member through the opening in the wall of the body member, and an adjustable connection between said arms.
- 10 7. In a rope clamp, a body provided with a longitudinally disposed opening extending therethrough, and with a longitudinal slot in the wall thereof communicating with said opening, the opening extending through the 15 body of the clamp being provided with a wall curved on the arc of a circle, a rigid arm projecting laterally from said body at one side of the longitudinal slot in the wall thereof, a sector shaped jaw member projecting into the longitudinally disposed opening in the body of the clamp, a sector shaped jaw member movably mounted in the opening extending through the body member and provided with a curved wall con- 20 forming to the curvature of the curved wall of said opening, an arm projecting laterally from said movable jaw member through the slot in the wall of the body member, and an adjustable connection between said arm and 25 the rigid arm projecting from the body of the clamp.
8. In a rope clamp, a body provided with an opening extending longitudinally therethrough, said opening having a wall curved 30 on the arc of a circle, the wall of said body being provided with a longitudinally disposed slot therein communicating with the opening extending through the body and with a laterally extending recess positioned 35 intermediate the top and bottom of the body and opening into the slot in the wall thereof, a jaw member rigid with said body and projecting into the opening extending longitudinally therethrough, a jaw member 40 movably supported in the opening extending longitudinally through the body and provided with a curved wall conforming to the curvature of the wall of said opening, a rigid arm projecting laterally from said body, an arm projecting laterally from the movable jaw member through the slot in the wall of the body of the clamp, said last mentioned arm being positioned to move in the laterally extending recess in the body of the clamp, and an adjustable connection be- 45 tween said arm and the rigid arm projecting from the body of the clamp. 50
9. In a rope clamp, a pair of jaw members, one of which is movable relative to the other, an arm extending from each of said jaw members, a block slidably mounted on one of said arms, a bail pivotally connected to said block and adapted to embrace the other of said arms, and an operating screw having a threaded engagement with said 55 block, the end of said screw being adapted to engage the arm supporting said block.
10. In a rope clamp of the character described, a body, a pair of jaw members supported in said body, means for adjusting one 60 of such jaw members relatively to the other to clamp a cable therebetween, said jaw members being held against movement in the body when in clamping engagement with a cable, a removable liner for each of said 65 jaw members, means for rigidly securing said liners to said jaw members, each of said liners being provided with a curved cable receiving recess, said cable receiving recesses being provided with straight parallel walls. 70
